[57] **CLAIM**

The ornamental design for a sink, as shown and described.

DESCRIPTION

FIG. 1 is a perspective view taken from the top, front and right side of a sink showing our new design;

FIG. 2 is a top plan view thereof;

FIG. 3 is a cross-sectional view taken on line 3—3 of FIG. 2;

FIG. 4 is a cross-sectional view taken on line 4—4 of FIG. 2; and

FIG. 5 is a cross-sectional view taken on line 5—5 of FIG. 2.

The broken line representation of holes and the fragmentary broken line representation of a counter top in FIG. 1 are for purposes of illustration only and form no part of the claimed design.

FIG. 1

FIG. 5

FIG. 3

FIG. 4
